[57] CLAIM

The ornamental design for a remote control adapter, as
shown and described.

DESCRIPTION

FIG. 1 is a top front and right side perspective view of
a remote control adapter showing my new design;

FIG. 2 is a front elevational view thereof;

FIG. 3 is a right side elevational view thereof, the left
side being a mirror image;

FIG. 4 is a rear elevational view thereof;

FIG. 5 is a top plan view thereof; and

FIG. 6 is a bottom plan view thereof.

The broken line showing the remote control in FIG. 1
is for illustrative purposes only and forms no part of the
claimed design.
